UNITED STATES PATENT OFFICE

110,539

DESIGN FOR A FAN OR SIMILAR ARTICLE

Abraham Fingerhut, Woodmere, N. Y.

Application May 20, 1938, Serial No. 77,315

Term of patent 7 years

To all whom it may concern:

Be it known that Abraham Fingerhut, a citizen of the United States and resident of Woodmere, in the county of Nassau and State of New York, has invented a new, original, and ornamental Design for a Fan or Similar Article, of which the following is a specification, reference being had to the accompanying drawings, forming part thereof, and in which,

Fig. 1 is a front perspective view of a fan or similar article, embodying my new design; and

Fig. 2 is a rear perspective view thereof.

The characteristic features of the design reside in the fan being provided with a body A of artificial flowers, carried at the upper end of a short handle B, to which is attached a wrist band C.

I claim:

The ornamental design for a fan or similar article, substantially as shown and described.

ABRAHAM FINGERHUT.
